UNITED STATES PATENT OFFICE.

FRANK A. GRIFFIN, OF HORNELL, NEW YORK.

SAFETY HAND-HOLE COVER FOR STEAM-BOILERS AND AIR AND OIL RESERVOIRS.

1,192,417.

Specification of Letters Patent. Patented July 25, 1916.

Application filed May 14, 1914. Serial No. 838,426.

To all whom it may concern:

Be it known that I, FRANK A. GRIFFIN, a citizen of the United States, residing at Hornell, in the county of Steuben and State of New York, have invented certain new and useful Improvements in Safety Hand-Hole Covers for Steam-Boilers and Air and Oil Reservoirs, of which the following is a specification, reference being had therein to the accompanying drawing.

My present invention relates to certain new and useful improvements in covers for hand-hole openings in the walls of boilers, air or oil reservoirs, and other receptacles, compartments or tanks of various kinds, the object being to enable easy access to be had to the tubes or fittings within the boiler for the purposes of cleaning, blowing out, etc.

One special purpose of my improved invention is to provide a safety hand-hole cover for the boiler sheet contiguous to the water tubes which support the arches in the fireboxes of locomotive and stationary engines so that the tubes may be examined with ease and safety.

The invention comprises numerous details and peculiarities in the construction, arrangement and combination of the various parts, substantially as will be hereinafter described and then more particularly pointed out in the claims.

In the accompanying drawing illustrating my invention: Figure 1 is a detail sectional view of a portion of a boiler wall and arch tube attached thereto and showing the position and arrangement of my improved safety hand-hole cover. Fig. 2 is a detail view showing the oval opening which receives the cover. Fig. 3 is an inner elevation showing the hand-hole cover in position, but with the nut removed. Fig. 4 is a horizontal section on the line 4, 4 of Fig. 6. Fig. 5 is a vertical section on the line 5, 5 of Fig. 6. Fig. 6 is an outer elevational view of the parts of my improved invention as they appear from the outside of the boiler wall. Fig. 7 is a modified sectional view of the invention.

Similar characters of reference designate corresponding parts throughout the different figures of the drawing.

In order to show one way of applying my invention to practical use, the same being simply for the sake of illustration, I have delineated in Fig. 1 a part of a boiler wall

having the outer sheet 1 and the inner sheet 2, while 3 denotes an arch tube which is connected to the inner sheet 2. It is, however, necessary that tubes like the tube 3, should be easy of access from without the boiler for inspection, cleaning, etc., and hence, it is necessary that the outer sheet 1 should be provided with a hand-hole, as at 4, and obviously such hand-hole must have a removable cover. While I have shown the boiler wall and arch tube, it should be understood that I have done so for explanatory purposes only and with no idea of being confined thereto, inasmuch as the invention is useful with all kinds of boilers and air or oil or fluid pressure tanks, reservoirs, etc.

Proceeding now to describe the details of the invention, I first state that the wall of the boiler, as for instance the outer sheet 1, or the wall of any other receptacle, is provided with an opening 4, which is of oval or oblong form, that is to say, of a form which has the axis in one direction longer than it is in the other direction, so that the opening is accordingly elongated. This opening 4 is directly opposite to the arch tube 3, or is otherwise so located as to permit access at the desired point. The cover for said oval opening 4 consists of an oval plate 6 provided with a flange 7 which forms a rabbet 8, and provided with a central inwardly projecting boss or shank 9 which is externally screw-threaded at 10 to receive thereon a nut 11. The cover 6 is inserted through the opening 4 from the outside by turning the same flatwise and passing it endwise through the oval opening 4, retaining hold at the same time of the boss 9 so that it may be shifted around with the hand from the outside and brought into a position where the flange 7 fits tightly against the inside face of the boiler sheet 1 immediately around the opening 4 and the rabbet 8 engages the edge of the opening 4 as clearly shown in Figs. 4 and 5. In order to enable the cover 6 to be more easily turned when it is being inserted through the opening 4, the edges thereof are slightly beveled at 18 as seen in Fig. 5.

Ordinarily, I employ a copper or other gas-
ket 12 between the flange 7 and the boiler plate 1. After the cover 6 has thus been placed in position with its rabbeted edge 8 engaging the edge of the oval opening 4 and with the shank or boss 9 projecting outwardly through the opening 4 and centrally therein, as shown in Fig. 1 and also in Figs.

4 and 5, the nut 11 can be screwed upon the screw-threaded exterior of the boss 9 and turned up tightly against the outer face of the boiler sheet 1, it being noted that the 5 inner surface of the nut 11 is preferably provided with a circular rib 13 which comes in close contact with the outer face of boiler sheet 1 close to the opening 4, said rib enabling a tighter joint to be effected than if 10 it were omitted and the flat face of the nut was turned up against the sheet 1. It will thus be seen that the nut by screwing upon the boss of the cover 6 will form a very tight and efficient locking combination, the parts 15 being tightly and securely held together.

Ordinarily the hand-hole cover 6 will be provided with a central passage 14, which in the case of the arch tube construction will be opposite to said tube 3, and the outer end 20 of the passage 14 is slightly tapered or beveled at 15, said beveled portion of the opening being furnished with a correspondingly tapered plug 16 having a head 17 thereon and adapted to be screwed tightly 25 into the opening for the purpose of closing the passage in the hand-hole cover. The screw plug can be removed whenever desired to permit access to the interior of the boiler wall whenever it is not necessary to 30 remove the hand-hole cover, as will often be the case. After the hand-hole cover and nut have been securely fastened together, the tapered screw plug can be fixed in place and the result is a perfect closing of the 35 opening 14.

A modification of the invention is shown in Fig. 7 where it is indicated as applied to a corner of the boiler wall, or to a curved surface. The only change in the device 40 when it is applied to rounding or curved surfaces instead of flat surfaces, is a corresponding change in the curvature of the cover so that it may conform to the shape of the wall, and sometimes the employment of 45 a washer between the nut and the wall to which the cover is applied. In Fig. 7 the cover 6^a is shown having the flange 7^a which seats against the inner surface of the boiler plate 1. Said cover 6^a has a shank 9^a which 50 is screw-threaded to receive the nut 11 having rib 13. Between nut 11 and the wall 1

is a washer 20 surrounding the shank 9^a and said washer has a curved face 21 which conforms to the shape of the wall 1. The cover 6^a is provided with a passage 14 ordinarily and also with a screw plug 16. 55

Many changes in the precise construction and arrangement of the various parts may be made without exceeding the scope of the claims or departing from the principles of 60 my invention.

Having thus described my invention, what I claim as new and desire to secure by Letters Patent, is:

1. In a safety hand hole cover, the combination with a wall or plate having an oval opening, of a correspondingly-shaped flanged cover having a central passage running through the same from one side to the other, and a screw-threaded boss around the 70 outer end of said passage, the inside of the passage being also screw-threaded for a distance, said cover being adapted to be passed through the oval opening from the outside and turned by hand and caused to fit snugly 75 over the opening on the inside, a nut screwing upon the screw-threaded boss and against the outside face of the wall, and a removable screw plug in the central passage.

2. In a safety hand hole cover, the combination with a wall or plate having an oval opening, of a correspondingly-shaped flanged cover having a central passage running through the same from one side to the other, and a screw-threaded boss around 85 the outer end of said passage, the inside of the passage being also screw-threaded and tapered for a distance, said cover being adapted to be passed through the oval opening from the outside and turned by hand 90 and caused to fit snugly over the opening on the inside, a nut screwing upon the screw-threaded boss and against the outside face of the wall, and a removable tapered screw plug in the central passage. 95

In testimony whereof I affix my signature in the presence of two witnesses.

FRANK A. GRIFFIN.
